Inventor

Jacob Hecler

United States Patent Office.

JACOB MILLER, OF WASHINGTON, PENNSYLVANIA.

Letters Patent No. 83,523, dated October 27, 1868.

IMPROVEMENT IN MACHINE FOR BENDING OVAL HANDLES FOR TIN-WARE.

The Schedule referred to in these Letters Patent and making part of the same.

To all whom it may concern:

Be it known that I, JACOB MILLER, of Washington, in the county of Washington, and State of Pennsylvania, have invented a new and useful Improvement in Machine for Bending "Oval Handles" for Tinmen; and I do hereby declare that the following is a full and exact description thereof, reference being had to the accompanying drawings, and to the letters and figures of reference marked thereon.

The nature of my invention consists in the use of a frame, provided with a guide-pin, and adjustable forms, which are used in connection with grooved rollers, for bending the wire for the handles around said adjustable forms, through the medium of levers, the whole being constructed, arranged, combined, and operating as hereinafter described.

To enable others skilled in the art to make and use my invention, I will proceed to describe its construction and operation.

In the accompanying drawings, which form part of my specification—

Figure 1 is a top view or plan of my improvement in machines for bending oval handles for tinmen.

Figure 2 is a side elevation of the same.

In the drawings, A is the frame, which is provided with slots, B and e, guide-pin J, and a foot, h. In the slots e are placed bolts, g, which are used in connection with screw-nuts, 2, for securing the forms C in the desired position on the frame A. The forms C are braced apart by means of the brace l. The levers D are pivoted on the bolts g, and provided with rollers, f, which are held to the levers by means of screw-nuts, 1.

The bending-machine may be adapted to different sizes of wire and handles, by the use of rollers and forms of different sizes, and by making the guide-pin J adjustable.

As the form, construction, and arrangement of the several parts of my improvement in machine for bending oval handles will be readily seen and understood, by reference to the accompanying drawings, I will therefore, without further description of their construction, proceed to describe their operation, which is as follows:

Having all things constructed and arranged as herein described and represented, and the wire cut off in suitable lengths, the wire is placed between the pin J and forms C, as indicated by the wire marked m.

The levers D are then forced around, as indicated by the arrows marked 3, until the levers are in the position shown by the red lines x', which will cause the rollers f to bend the wire around the forms C, as shown in red at x, thereby forming a uniform and perfect oval handle for the use of tinmen.

Having thus described the nature, construction, and operation of my improvement,

What I claim as of my invention is—

The frame A, provided with the slots B and e, pin J, forms C, and brace l, and used in combination with levers D, provided with rollers f, constructed, arranged, and operating as herein described, and for the purpose set forth.
